UNITED STATES PATENT OFFICE.

HANS GRADE, OF MAGDEBURG, GERMANY.

EXPLOSIVE-ENGINE.

No. 873,857.

Specification of Letters Patent.

Patented Dec. 17, 1907.

Application filed August 7, 1905. Serial No. 273,121.

To all whom it may concern:

Be it known that I, HANS GRADE, a subject of the King of Prussia, residing at Magdeburg, German Empire, have invented certain new and useful Improvements in Explosive-Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to two-stroke cycle explosive engines which compress the new charge preliminarily in the crank chamber for the purpose of expelling the old mixture and has for its object the separating the exhaust gases from the new charge in the passage leading from the inlet valve to the cylinder by means of a pure air layer or zone produced by means of an inlet valve, which at the same time lets pass or forms this charge mixture and serves also when using liquid fuel as a means for heating this fuel in a preliminary manner and volatilizing it.

Referring to the drawing in which like parts are similarly designated, Figure 1 is a vertical longitudinal section of a motor showing the inlet valve embodying my invention attached. Fig. 2 is a vertical longitudinal section of another form of the inlet valve embodying my invention. Fig. 3 is a front view of the inlet valve seat in Fig. 2.

The inlet valve Fig. 1 is shown in connection with a two-stroke cycle motor designed for using a gaseous combustible. The cylinder or combustion chamber 10 is provided with an inlet port 11, for the mixture of air and gas and an exhaust port 12 controlled by the piston 18 through which port the products of combustion are expelled.

Below the cylinder 10 is the closed crank chamber 13 having bearings 14 for the crank shaft 15 that is connected by the piston rod 17 to the piston 18 in any suitable manner.

Between the cylinder 10 and the crank case 13 that acts as a pump chamber, is a by-pass 19 and in the side of this passage 19 is placed the seat for the inlet-valve.

The pipe 21 for combustible mixture terminates and is controlled by substantially the lower half of the inlet valve 23 as shown and adjacent the pump chamber 13 so that the upper part of the valve will control the passage of air through its seat 20, this being

exposed at the part 22 to the outer air, so that when the valve is opened the outer air will pass through substantially the upper part 22 of the valve seat through the inlet-port 11 into the cylinder. The valve 23 is normally held to its seat 20 by means of spring 24 in the usual manner.

In the modification shown in Figs. 2 and 3 the mixture is produced by the inlet valve 65 itself. The inlet valve consists of a casing or seat *a* mounted on the cylinder 3 and of a plate or disk *c*. The seat *a* has a central opening 1 forming a channel for supplying air and is provided with a spider 4 carrying a 70 guide sleeve 5 for the stem of the valve disk *c*. This seat has also an annular channel *b* closed at its inner side by a ring 6 adapted and soldered to the seat *a*. The disk *c* is provided with a stem 7 having mounted on it a washer 8 and between this washer 8 and the spider 4 a spring 9 is arranged pressing the valve disk *c* against the seat *a*. Openings or nozzles *d* extend from the channel *b* to the seat surface. For liquid fuel these openings *d* are arranged 75 in a small number (for example 2-4) and are smaller, and for gas they are arranged in a greater number (for example 7-10) and are broader. These openings are provided only in the under half of the valve seat, which 80 under half is arranged towards the crank chamber, and are closed by the valve disk *c* itself, this being possible owing to the small displacing pressure, as it takes place in other constructions in a similar manner but in 85 using a special fuel valve situated before the inlet valve. The fuel is supplied to the annular channel *b* through a threaded inlet pipe *e*.

The operation of the form shown in Fig. 1 is as follows: By the upward movement of the 90 piston 18 the inlet valve 23 is automatically opened by reason of the suction action of the piston and through the upper part of its seat air is drawn into the by-pass 19 and through 95 the lower part combustible mixture and both are conducted through 19 into the crank case 13. As soon as the piston is driven downwards by the ignition of the gases, the inlet-valve 23 closes and the air and gas mixture in the 100 crank case are compressed. Then when the piston 18 uncovers the inlet-port 11 the compressed gases in 13 and 19 are driven into the cylinder 10.

Since during the up stroke of the piston gas was admitted from substantially only the lower half of the valve and air 105 only through the upper half, there is during the upward travel of the piston a quantity of

air in the upper part of the by-pass 19 which when the piston 18 uncovers port 11 will enter the cylinder first and form a separating layer between the spent gases and the new charge.

In both cases, *i. e.* in the modification according to Fig. 1 and in that according to Figs. 2 and 3 the inlet valve is situated as in similar arrangements at the side of the passage and leading from the crank case to the cylinder, but with its axis lying horizontally.

When suction takes place only pure air flows through the upper half of the opening of the channel 1 released by the valve disk *c* into the passage *f* and fills the upper space. On the under half, on the contrary, either the finished mixture enters or the entering air sucks the fuel from the openings *d* and mixes with it, whereat liquid fuel is heated in a preliminary manner at the same time in the annular channel *b*. Therefore the usual non-inflammable isolating layer drawn through the upper half of the opening of the inlet valve is placed between the exhaust gases of the preceding explosion and the new mixture. With regard to the other engines, the separating layer is produced by auxiliary channels, special valves or mixture chambers etc., but in my invention the separating layer is produced by the arrangement of the valve on the passage leading to the cylinder and by supplying the mixture or the fuel from one half of the valve.

Having thus described my invention, what I claim as new therein and desire to secure by Letters Patent, is:—

1. In a two-stroke cycle explosion engine the combination with the combustion chamber and the crank chamber of a by-pass connecting them, a valve in said by-pass and means to admit air from the valve to said by-pass and combustible from substantially one-half of this valve nearest the crank chamber to said by-pass, substantially as described.

2. In a two-stroke cycle explosion engine the combination with the combustion cham-

ber and crank chamber of a by-pass connecting them, a valve and valve seat in the side of said by-pass, means to admit air through the valve and fuel admission ports in a portion of the seat adjacent the crank chamber and controlled by said valve, substantially as described.

3. In a two-stroke cycle explosion engine the combination with the combustion chamber and the crank chamber acting as a pump chamber of a by-pass between them, a valve and valve seat in the side of said by-pass, means to permit the passage of air through the valve, an annular channel formed in the valve seat, fuel out-let-openings from said passage through the seat over substantially only one-half the circumference thereof nearest the crank chamber, said openings controlled by the valve.

4. In a two-stroke cycle explosion engine the combination with the combustion chamber having inlet and exhaust ports controlled by the piston and a crank chamber of a by-pass extending from the inlet port to the crank chamber, a valve admitting both combustible and air to said by-pass, the combustible being admitted through substantially one-half of the valve nearest the crank chamber.

5. In a two-stroke cycle explosion engine, the combination with the combustion and the crank chambers; of a by-pass connecting them, a valve and a valve seat in said by-pass, means to supply both air and combustible to different portions of the valve and said valve controlling both the admission of air and combustible, the combustible being admitted through that portion of the valve nearest the crank chamber.

In testimony that I claim the foregoing as my invention, I have signed my name in presence of two subscribing witnesses.

HANS GRADE.
